UNITED STATES PATENT OFFICE.

ALVARO S. KROZT, OF CHICAGO, ILLINOIS.

INTERNAL-COMBUSTION ENGINE.

1,016,335.

Specification of Letters Patent.

Patented Feb. 6, 1912.

Application filed February 19, 1910. Serial No. 544,849.

To all whom it may concern:

Be it known that I, ALVARO S. KROZT, a citizen of the United States of America, and a resident of Chicago, in the county of 5 Cook and State of Illinois, have invented certain new and useful Improvements in Internal-Combustion Engines, of which the following is a specification.

This invention relates to certain improvements in internal combustion engines and the means for positively introducing the explosive charges of mixed air and vapor into the explosion chambers of the same. And the present improvement has for its object 10 to provide a simple and efficient pumping mechanism operating in unison with the engine and adapted to positively introduce successive charges of mixed air and vapor into the explosion chamber of the engine 15 during the continued operation of the same, all as will hereinafter more fully appear.

In the accompanying drawings:—Figure 1, is a central longitudinal sectional elevation of a four-cycle engine to which the 20 present invention is applied. Fig. 2, is a transverse section on line $x-x$, Fig. 1. Fig. 3, is an enlarged detail longitudinal sectional elevation of the fuel feeding pump.

Similar numerals of reference indicate 25 like parts in the several views.

Referring to the drawings, 1 represents the engine cylinder preferably of the air cooled type; 2 the chambered or skirted piston, and 3 the usual closed casing to 30 which one end of the cylinder is secured in the usual manner. Such casing is provided with the usual bearings for the crank shaft and for other usual mechanisms of the engine.

40 4 is the exhaust neck or passage of the cylinder 1, having communication with the interior of said cylinder at a point which is only uncovered by the piston 2 when the same is at the end of its outward stroke.

45 5 is an exhaust pipe extending from the aforesaid neck 4 and preferably connected to the air heater hereinafter described.

6 is a transverse ridge or projection on the inner and closed head of the skirted 50 piston 2. Said ridge is of an angular form with its vertical wall next adjacent to the hereinafter described air inlet passage in the wall of the cylinder 1 and with its inclined portion sloping toward the aforesaid exhaust neck 4, as shown, the formation being

adapted to materially aid in the removal of the exploded charge from the cylinder by means hereinafter described.

7 is a longitudinal passage formed in a side of the cylinder 1 opposite to the exhaust neck 4, aforesaid. One end of said passage communicates with the interior of the cylinder on a plane with the said exhaust neck 4, while its other end is adapted to register with a port 8 formed in the skirt 60 of the piston 2, so that when said port and passage are in register the passage will form a communication between the respective chamber of the cylinder 1 and casing 65 3, aforesaid.

9 is a curved deflecting plate arranged in one side of the chamber of the piston 2, and immediately in front of the port 8 thereof. Said deflecting plate is adapted to cause an indirect and very effective circulation of the air in the interior of the piston as said air passes from the casing 3 into the explosive chamber of the cylinder 1, to aid materially in carrying off the heat accumulating in said piston during a continued 70 80 operation of the engine.

10 is a crank shaft journaled in the casing 3, and having a pitman connection 11 with the engine piston 2, as usual.

12 is a disk valve member fixedly secured 85 to the crank shaft 10 and having a seat or bearing against an end of the casing 3. Said valve member is formed with a segmental slot or port 13, adapted at proper intervals in its travel in a circular path to register 90 with an air inlet passage 14 in the casing 3, as shown in Figs. 1 and 2.

15 is a countershaft journaled on the casing 3, and having operative connection with the crank shaft 10, by a pair of gear wheels 95 16 and 17, having proportionate diameters of one to two as illustrated in Fig. 1.

18 is a spark plug, the energizing electric current to which is controlled by the movement of the engine in the usual manner.

19 is a cam carried by the countershaft 15 aforesaid, and adapted to impart longitudinal movement in one direction to a rod 20, one end of which preferably constitutes the secondary pump piston or plunger hereinafter described. Movement of said rod in the opposite direction is attained by a spring 21, as illustrated in Fig. 1.

22 is a pump casing formed with a liquid fuel piston chamber and an air and liquid 110

fuel piston chamber arranged in parallel relation, the diameter of the last named chamber being largely in excess of the first named piston chamber, as illustrated in 5 Fig. 3.

23 is the piston or plunger of the liquid fuel piston chamber aforesaid, and 24 is the piston or plunger of the air and liquid fuel piston chamber aforesaid and preferably 10 formed by the upper end of the rod 20 above described.

25 is a cross-head connecting the two pistons together to impose simultaneous movement upon the same.

15 26 is a supply pipe extending from a suitable supply of liquid fuel, and connected to an inlet port which opens into the liquid fuel piston chamber aforesaid of the pump midway the length of said chamber, as 20 shown.

27 is a needle or like valve arranged in the supply pipe 26 and adapted to throttle the passage in said pipe to suit varying requirements in the continued operation of 25 the engine.

28 is an outlet passage from the end of 30 the liquid fuel piston chamber, and containing a check valve 29 intermediate its length. Such passage is of the tortuous form shown in Fig. 3, and its outlet end opens into a transparent walled chamber 30, carried by 35 the pump casing and enabling the operator to view the flow of liquid fuel from said passage. 31 is an air inlet pipe also opening into said transparent walled chamber 30 in common with the outlet passage 28 aforesaid. Said inlet pipe is adapted to introduce a supply of air from a suitable source, 40 preferably from the preheating attachment hereinafter described.

32 is the inlet passage of the air and liquid fuel piston chamber aforesaid; said passage opens at one end into said piston chamber midway its length, and at the other end 45 opens into the bottom of the transparent walled chamber 30, aforesaid. 33 is the outlet passage from the end of said air and liquid fuel piston chamber and contains a check valve 34 intermediate its length. The 50 inclosing wall of said passage is adapted for connection to the upper end of the explosion chamber of the engine as shown in Fig. 1, and preferably ending in a discharge nozzle 35 of any usual form.

55 36 is a casing surrounding a portion of the exhaust pipe 5 of the engine and attached to said pipe by end heads as shown. Near one end said casing is provided with a series of inlet orifices 37 for air, and near 60 the opposite end has communication with the air pipe 31, which extends to the fuel feeding pump as heretofore described.

The described arrangement of parts is adapted to afford a very durable and efficient preheating attachment for heating 65

the air which is supplied to the fuel feeding pump to aid in vaporizing the liquid fuel.

The operation of the engine proper is as follows: Following an explosion within the engine cylinder 1, the piston 2 moves outward within said cylinder compressing the air contained in the casing 3, and as it reaches its full out stroke uncovers the exhaust port 4, to permit the escape of the spent gases, and at the same time registers 75 the piston port 8 with the passage 7 to permit the compressed air in the casing 3 to flow into the cylinder 1 and aid in expelling the spent gases. During such operation the port 13 of the valve member 12 is out of register with the air inlet passage 14, so that there is no leakage at such point. With an inward movement of the piston 2, the exhaust port 4 is closed, as well as the passage 7, and at the same time the port 13 is 80 brought into register with the air inlet passage 14 to permit a fresh supply of air to be drawn into the casing 3, by the piston in its inward movement. The above described inward movement of the piston 2, as 85 well as the succeeding outward and inward movements of the piston are inactive ones and are attained by the momentum of the engine shaft, fly wheel, etc. to effect a scavenger action in the cylinder. The next 90 succeeding outward movement of the piston is an active one in the cycle, and at or before its commencement the fuel feeding pump has its action so timed as to inject a supply of fuel into the cylinder. Immediately 100 such fuel injection occurs the spark plug 18 operates to fire the charge.

The operation of the pumping mechanism by which the fuel is positively forced into the engine cylinder is as follows:—The air 105 and liquid fuel piston 24, receives an inward and outward movement in its piston chamber by the described connection with the engine shaft 10. The outward movement of said piston 24 is adapted to create a 110 partial vacuum in its piston chamber until said piston near the end of its outward movement and uncovers the inlet port or passage 32 to permit the mixed air and liquid fuel which is in the chamber 30 to 115 flow into the piston chamber aforesaid and fill the previously existing vacuum in the same. Said supply of air and liquid fuel is attained through the air supply passage 31, and the liquid fuel supply passage 28. 120 Coincident with the above described outward movement of the air and liquid fuel pump piston 24, the liquid fuel piston 23 has an outward movement in its piston chamber and is adapted to create a partial 125 vacuum therein, until said piston 23 nears the end of its outward movement and uncovers the liquid fuel inlet passage or port 26, to permit the liquid fuel from a suitable 130 source of supply to flow into piston cham-

ber of the piston 23 and fill the previously existing vacuum in the same. The inward movement of the air and liquid fuel pump piston 24, in its piston chamber, forces the 5 air and liquid fuel contained in said piston chamber past the outlet check valve 34, and through the passage 33 and discharge nozzle 35, into the explosion chamber of the engine, and such discharge takes place at 10 the before described period in the operation of the engine. Coincident with such inward movement of the air and liquid fuel piston 24, the liquid fuel piston 23 has an inward movement in its piston chamber, to force the 15 liquid fuel contents of said chamber past the outlet check valve 29 and through the passage 28 into the chamber 30, to provide a supply of liquid fuel for the succeeding outward stroke of the aforesaid air and liquid 20 fuel piston 24.

Having thus fully described my said invention what I claim as new and desire to secure by Letters Patent, is:—

1. A combined fuel and air feeding pump 25 for internal combustion engines comprising, a primary and secondary piston connected for simultaneous reciprocation, a pump casing formed with primary and secondary piston chambers for said pistons, an air supply pipe having connection with the outlet passage from the secondary piston chamber and with the inlet passage to the primary piston chamber, a liquid fuel pipe connected with the inlet port of the secondary piston 30 chamber, and an outlet casing having connection with the outlet port of the primary piston chamber and with the explosion chamber of the engine, and means for imparting reciprocation to said pistons, substantially as set forth.

2. A combined fuel and air feeding pump 45 for internal combustion engines comprising, a primary and secondary piston connected for simultaneous reciprocation, a pump casing formed with primary and secondary piston chambers for said pistons, an air supply pipe having connection with the outlet passage from the secondary piston chamber and with the inlet passage to the 50 primary piston chamber, a liquid fuel pipe connected with the inlet port of the secondary piston chamber, an outlet casing having connection with the outlet port of the primary piston chamber and with the explosion chamber of the engine, means for preheating the air passing through the aforesaid air supply pipe, and means for imparting reciprocation to said pistons, substantially as set forth.

60 3. A combined fuel and air feeding pump for internal combustion engines comprising a primary and secondary piston, a cross-head connecting said pistons together for simultaneous reciprocation, a pump casing 65 formed with primary and secondary piston

chambers for said pistons, an air supply pipe having connection with the outlet passage of the secondary piston chamber and with the inlet passage to the primary piston chamber, a liquid fuel pipe connected with the inlet port of the secondary piston chamber, an outlet casing having connection with the outlet port of the primary piston chamber and with the explosion chamber of the engine, and means for imparting reciprocation to said pistons, substantially as described.

4. A combined fuel and air feeding pump for internal combustion engines comprising a primary and secondary piston, a cross-head connecting said pistons together for simultaneous reciprocation, a pump casing formed with primary and secondary piston chambers for said pistons, an air supply pipe having connection with the outlet passage of the secondary piston chamber and with the inlet passage to the primary piston chamber, a liquid fuel pipe connected with the inlet port of the secondary piston chamber, an outlet casing having connection with the outlet port of the primary piston chamber and with the explosion chamber of the engine, means for preheating the air passing through the aforesaid air supply pipe, and means for imparting reciprocation to said pistons, substantially as described.

5. A combined fuel and air feeding pump for internal combustion engines comprising, a primary and secondary piston connected for simultaneous reciprocation, a pump casing formed with primary and secondary piston chambers for said pistons, a chambered casing carried by the pump casing and having connection with an air supply and with the outlet port of the secondary piston 100 chamber and inlet port of the primary piston chamber, a liquid fuel pipe connected with the inlet port of the secondary piston chamber, an outlet casing having connection with the outlet port of the primary piston chamber and with the explosion chamber of the engine, and means for imparting reciprocation to said pistons, substantially as set forth.

6. A combined fuel and air feeding pump 115 for internal combustion engines comprising, a primary and secondary piston connected for simultaneous reciprocation, a pump casing formed with primary and secondary piston chambers for said pistons, a chambered casing carried by the pump casing and having connection with an air supply and with the outlet port of the secondary piston chamber and inlet port of the primary piston chamber, a liquid fuel pipe connected with the 120 inlet port of the secondary piston chamber, an outlet casing having connection with the outlet port of the primary piston chamber and with the explosion chamber of the engine, means for preheating the air passing 125 through the aforesaid air supply pipe, and means for imparting reciprocation to said pistons, substantially as described.

through the aforesaid air supply, and means for imparting reciprocation to said pistons, substantially as set forth.

7. A combined fuel and air feeding pump for internal combustion engines comprising a primary and secondary piston, a cross-head connecting said pistons together for simultaneous reciprocation, a pump casing formed with primary and secondary piston chambers for said pistons, a chambered casing carried by the pump casing and having connection with an air supply and with the outlet port of the secondary piston chamber and inlet port of the primary piston chamber, a liquid fuel pipe connected with the inlet port of the secondary piston chamber, an outlet casing having connection with the outlet port of the primary piston chamber and with the explosion chamber of the engine, and means for imparting reciprocation to said pistons, substantially as set forth.

8. A combined fuel and air feeding pump for internal combustion engines comprising a primary and secondary piston, a cross-head connecting said pistons together for simultaneous reciprocation, a pump casing formed with primary and secondary piston chambers for said pistons, a chambered casing carried by the pump casing and having connection with an air supply and with the outlet port of the secondary piston chamber and inlet port of the primary piston chamber, a liquid fuel pipe connected with the inlet port of the secondary piston chamber, an outlet casing having connection with the outlet port of the primary piston chamber and with the explosion chamber of the engine, means for preheating the air passing through the aforesaid air supply, and means for imparting reciprocation to said pistons, substantially as set forth.

9. A combined fuel and air feeding pump for internal combustion engines comprising, a primary and secondary piston connected for simultaneous reciprocation, a pump cas-

ing formed with primary and secondary piston chambers for said pistons, an air supply pipe having connection with the outlet passage from the secondary piston chamber and with the inlet passage to the primary piston chamber, a liquid fuel pipe connected with the inlet port of the secondary piston chamber, an outlet casing having connection with the outlet port of the primary piston chamber and with the explosion chamber of the engine, and means for imparting reciprocation to said pistons, the same comprising a countershaft operatively connected to the engine shaft, and a cam carried by said countershaft and having operative engagement with the primary piston, substantially as set forth.

10. A combined fuel and air feeding pump for internal combustion engines comprising a primary and secondary piston, a cross-head connecting said pistons together for simultaneous reciprocation, a pump casing formed with primary and secondary piston chambers for said pistons, an air supply pipe having connection with the outlet passage of the secondary piston chamber and with the inlet passage to the primary piston chamber, a liquid fuel pipe connected with the inlet port of the secondary piston chamber, an outlet casing having connection with the outlet port of the primary piston chamber and with the explosion chamber of the engine, and means for imparting reciprocation to said pistons, the same comprising a countershaft operatively connected to the engine shaft, and a cam carried by said countershaft and having operative engagement with the primary piston, substantially as set forth.

Signed at Chicago, Illinois, this 15th day of February, 1910.
